UNITED STATES PATENT OFFICE.

JOSEPH WOLFF, OF BROOKLYN, NEW YORK, ASSIGNOR TO SONORA PHONOGRAPH CORPORATION, A CORPORATION OF NEW YORK.

SOUND CONVEYER FOR TALKING MACHINES.

Application filed October 19, 1918. Serial No. 258,898.

To all whom it may concern:

Be it known that I, JOSEPH WOLFF, a subject of the King of Great Britain and Ireland, and a resident of the borough of Brooklyn, county of Kings, city and State of New York, have invented a certain new and useful Improvement in Sound Conveyers for Talking Machines, of which the following is a specification.

10 My invention relates to improvements in sound conveyers for talking machines, and contemplates the provision of means to improve the acoustic and resonant qualities of the reproduction.

15 One of the objects of my invention is to so improve and construct the sound conveyer for talking machines that the resonance and qualities of the reproduced sound will be increased, greatly improved and intensified, 20 and to eliminate the "brassy" and metallic sound so prevalent in talking machines.

25 A further object of my invention is the construction and arrangement of a sectional sound conveyer for talking machines, so that it can be adopted for playing records having lateral undulations, and for playing records having the vertical or hill-and-dale cut, and having means so that the sound-box may be quickly and easily substituted 30 for playing either style of records, and refers more particularly to the means employed to connect the several sections together and maintain a rigidity, flexibly within certain limits.

35 Another object of my invention is to allow the section of the arm to which the sound-box is immediately attached to be easily, quickly and securely attached to the main portion or section of the conveyer.

40 A further object of the invention is the provision of means of the character described, which are extremely simple in construction, neat and attractive in appearance, thoroughly reliable and efficient in purpose 45 and operation and inexpensive and economical to manufacture.

With these and other objects in view, to be more fully set forth hereinafter, the invention consists in the novel construction, 50 combination of elements, and arrangement of parts, which will be exemplified in the construction hereinafter described in the specification and illustrated in the accompanying drawings considered together or separately.

The inventive idea involved is capable of receiving a variety of mechanical expressions, one of which for the purpose of illustrating the invention, is shown in the accompanying drawings.

60 The invention will be first described in connection with the accompanying drawings illustrating one embodiment of my invention, wherein similar reference characters are used to designate corresponding parts throughout the several views, and then more specifically defined and indicated in the appended claim.

In the drawings,—

Fig. 1 is a side elevation in section of 70 a sound conveyer embodying my invention, with a sound-box in position for playing vertical cut records.

Fig. 2 is a side elevation of the same, with a sound-box segment in position for playing 75 records having lateral undulations, substitute for that shown in Fig. 1.

Fig. 3 is a detail of the bayonet joint connection between the sound-box carrying segment of the arm, and the fixed portion thereof.

Fig. 4 is a sectional detail view of a universal joint, take on the line $x-x$ in Fig. 5.

Fig. 5 is a detail view of the universal 80 joint, with the joint portion in vertical section, and the tubular portion in elevation.

In carrying out my invention, I employ a wooden sound conveyer, having a stationary member 1 provided with a sound-passage 2 of greater diameter than the sound 85 passage of the adjoining section; the lower end or base of the sound conveyer being formed with a circular projection 3, supplemental to a flange 4, to project into and rest upon an opening in a motor board partition, not illustrated.

90 In the upper end 5 of the sound conveyer 1, is arranged a universal joint 6 which connects with a movable arm segment 8 having a sound passage of less diameter than the member 1, and being provided with a metallic tubular part 7 projecting into the arm segment 8 and the sound conveyer 1 for the purpose of forming a tight joint, and as I have discovered that the use of such 95 a brass tube greatly improves and intensifies the acoustic and resonant qualities of the reproduction. The arm segment is connected by a bayonet joint 9 to the stylus-box carrying segment 10.

A concave recess 11 at the end of the segment 8 keeps it in close relation to the end 5 of the sound conveyer 1 while not in actual contact therewith.

5 In Fig. 2, I have illustrated a stylus-box holding segment 13 for playing records having lateral undulations. The universal joint has an outer metal ring 14 fitted securely into the inside of end 5 of the sound conveyer 1, by ring 23 forming part thereof. Within the ring 14 is a member 15 pivoted thereto by pins 18, 18. The head 16 of the tube 7 is pivoted to the member 15 by pins 17, 17. The sound-box carrying member and the movable arm segment are held together by a bayonet joint having a portion 19, and carrying upon its interior a pin or projection 20, which engages with slot 22 upon a cylindrical member 21 entering the portion 19.

10 The operation is as follows:

The sound conveyer 1 being placed in position by forcing the projecting portion 3 into a circular opening, and bringing the flange 4, down upon the surface of the partition or motor board, the arm is in operative position, and the arm segment 8 connected to the sound conveyer 1 by the universal joint 6 is free to vibrate horizontally or vertically, by reason of the vertical and horizontally arranged pivots in the universal joint.

15 In this connection it is essential to note that the openings in the interior of the sound conveyer 1 and segment 8, are practically one and continuous; and to the end that the exterior air be excluded, and the sound waves uninterrupted, I have provided the tubular portion 7 of the universal joint, which together with the bayonet joint 9 forms an arm as perfect for my purpose as though cast of metal in one piece or constructed of a solid piece of wood, etc.

20 The sound waves passing from the stylus box toward the elbow meet with no obstruction, but follow the contour of the interior of the arm until they change their direction in the enlarged space of the sound conveyer.

25 I find this abrupt enlargement at this point productive of excellent results, as it prevents the crowding and retardation

which would follow a change of direction were the curve of the same diameter as the horizontal opening.

I also find a bayonet joint of vulcanized fibre, the most convenient and effective form of connection, as it is practically as unresponsive to vibrations as the material in the rest of the arm; and finally, I find that a wooden arm made in segments is cheaper to manufacture.

30 In accordance with the provisions of the patent statutes, I have described the principle of my invention together with the apparatus which I consider represents the best embodiment thereof; but I desire it understood that my invention is not confined to the particular form of apparatus herein shown and described, the same being merely illustrative, and that the invention can be carried out in other ways without departing from the spirit of my invention, and therefore, I claim broadly the right to employ all equivalent instrumentalities coming within the scope of the appended claim, 35 and by means of which the objects of my invention are attained, and the new results accomplished, as herein set forth; as it is obvious that the particular embodiment herein shown and described, is only one of many 40 that can be employed to attain these objects and accomplish these results.

35 Having described my invention, what I claim and desire to secure by Letters Patent is as follows:—

45 In a tone arm for talking machines, a stationary tubular member and a movable tubular member, one of said members provided with a bell-shaped end piece which overlaps and conceals the end of the other member, 50 means concealed by said members for securing said members in overlapped but spaced apart relation, said means including a tube fitting tightly within the bore of one of the members and supported by gimbels 55 within the bore of the other member.

55 This specification signed and witnessed this 24th day of September, 1918.

JOSEPH WOLFF.
